Patented Nov. 14, 1916.

UNITED STATES PATENT OFFICE.

CHATTIN BRADWAY, OF BROOKLYN, NEW YORK, ASSIGNOR TO JUDSON H. BRADWAY,
OF NEW YORK, N. Y.

SOAP-BUBBLE BLOWER.

1,205,123.

Specification of Letters Patent.

Patented Nov. 14, 1916.

Application filed June 2, 1915. Serial No. 31,705.

To all whom it may concern:

Be it known that I, CHATTIN BRADWAY, a citizen of the United States, residing at Brooklyn, in the State of New York, have invented new and useful Improvements in Soap-Bubble Blowers, of which the following is a specification.

This invention relates to soap bubble pipes and it has for its general object to provide a multi-bubble pipe of simple and novel construction which embodies a plurality of bubble-forming chambers arranged concentrically, and each having an independent air inlet whereby air can be supplied to any of the chambers in any desired order for the production of concentric bubbles, chain bubbles, cluster bubbles and composite bubbles, such as chain and inclosed bubbles, cluster-inclosed bubbles, chain inclosed bubbles, etc. For a more complete understanding of the invention, reference is to be had to the following description and claims taken in connection with the accompanying drawing, which embodies a few of the various forms which the invention may take.

Referring to the drawing, Figure 1 is a perspective view of a multi-bubble pipe of the valve type. Fig. 2 is a vertical section thereof. Fig. 3 is a horizontal section showing the manner of supplying air to the several bubble-forming chambers. Fig. 4 is a perspective view of a key controlled multi-bubble pipe. Fig. 5 is a detail sectional view of one of the air-controlling keys. Fig. 6 is a perspective view of a double chamber lip-controlled pipe. Fig. 7 is a vertical sectional view of a quadruple-chamber lip-controlled pipe. Fig. 8 is a sectional view on line 8-8, Fig. 7. Fig. 9 is a perspective view of the mouth piece used on the pipe shown in Fig. 7. Figs. 10 to 14 are serial views respectively of single, inclosed, cluster, chain, and chain inclosed bubbles.

Referring to the drawings, the pipes shown are, with the exception of the two chamber pipe in Fig. 6, of the four chamber type, but the number of chambers may be varied as desired.

The body A of the pipe is provided with four chambers designated 1, 2, 3 and 4 respectively, one surrounding the other in the order mentioned and the lower ends of the chambers are open and the bottom edges 5 of the walls 6 are stepped from the outer to the inner one.

The chambers have respectively air supply passages 1^a, 2^a, 3^a and 4^a. In the construction shown in Figs. 1, 2 and 3, the user blows into any one of these passages through a single hollow stem 7 which is fastened to a band 8 that encircles the body A and is confined in a circumferential groove 9. This band forms a valve which closes all the passages except the one in line with the stem and as the band can slide around the body A the stem can be moved progressively or successively into and out of line with the openings for producing a succession of bubbles.

If air be blown into the passage 1^a first, a bubble will be formed from the chamber 1, and if the stem be successively moved to the passages 2^a, 3^a and 4^a while the user continues to blow, a series of four concentric bubbles will be produced.

If the blowing begins when the stem is in line with the passage 4^a and the stem is moved successively therefrom to the dotted line positions Fig. 3, a chain of bubbles will result. After this chain is produced, the stem can be moved back again, and three concentric bubbles will be formed in the uppermost bubble of the chain.

With this form of pipe any of the bubbles shown in Figs. 10, 11, 13 and 14 can be obtained and certain of the clusters in Fig. 12. The body A has a knob a on its top which can be grasped for turning the body in the band while the stem is held in the mouth.

According to Figs. 4 and 5, the air is controlled by valves in the form of depressible keys 1^b, 2^b, 3^b and 4^b which are fingered very much like the keys of a cornet, each key compressing a piece of rubber tubing 10 in the stem 11. There will be a rubber tube 10 communicating with each chamber of the pipe body or bowl to supply air thereto. The resiliency of the rubber will keep the keys raised and the tubes open so that air can freely pass from the mouth to the bubble forming chambers. The keys can be pressed in any desired order to obtain any of the bubbles shown in Figs. 10, 11, 13 and 14. By blowing simultaneously into two or more of the chambers in the body, the cluster bubbles shown in Fig. 12 can be made.

Referring to the lip-controlled pipe shown in Fig. 6, the body A¹ has two bubble-forming chambers 1^c and 2^c respectively, supplied with air blown through the individual stem pipes 12 and 13, which have a mouth piece 110

14 that has lower and upper apertures 16 and 17 for the pipes 12 and 13. The upper hole 16 can be closed by pressing the upper lip over it while air is blown from the mouth through the lower hole and after the large bubble is blown, the upper hole can be uncovered and air blown through both holes whereby an inner bubble will be formed while the outer or first one continues to enlarge. By closing the lower hole with the lower lip while the air is blown through the upper hole, a bubble will be formed by the inner chamber 2^c and then if air is blown through the lower hole a bubble will form from the chamber 1^c, dislodging but suspending the first bubble, so that a composite or primary chain bubble will be formed as the first one in Fig. 13. With this type of pipe various cluster bubbles can be obtained by blowing into both holes at once.

This type of pipe can be made with more chambers, as shown in Fig. 7 wherein the chambers 1^a, 2^a, 3^a and 4^a have separate pipes 1^e, 2^e, 3^e and 4^e for supplying air thereto. In order to provide for the proper "lapping" of the pipes, a mouth piece 17 is attached. This mouth piece has passages 1^f, 2^f, 3^f and 4^f communicating with the pipes 1^e, 2^e, 3^e and 4^e and these passages terminate as openings 18 in the curved surface 19 of the mouth piece. These openings are disposed in a horizontal line and the surface 19 is curved to fit the lips. In using the device, the surface 19 is pressed against the lips and air can be blown into any of the openings 18 according to the bubble formations desired. The surface 19 is smooth so that it can be moved horizontally while pressed against the lips which are held very much as they are when whistling so that air is ejected through a small opening about the size of each opening 18. By opening the mouth the mouth piece can be taken partly into the mouth and air blown into all the openings 18 at once for making cluster bubbles or for blowing large concentric bubbles after such concentric bubbles are successively blown by using the openings 18 successively. With this form of pipe all the bubbles shown in Figs. 10 to 14 can be made.

It is important that in forming one bubble within another that only one opening or pipe stem be open at a time, and the other openings or stems be kept closed. For instance, if a bubble be formed by the outermost chamber and this bubble be blown large, the pressure in the bubble acting on the films in the other chambers would be above atmosphere pressure and if the openings or stems leading to these other chambers were not closed, the films therein would break. Thus

in Fig. 7, when air is being blown into one opening 18 the other openings are kept closed by the mouth piece being pressed against the lips. The band valve in Fig. 1 and the keys in Fig. 4 make it possible to close the chambers and opening them successively as the concentric bubbles are made.

It is advantageous to direct the air into the chambers radially, in the form of pipes shown in Figs. 6 and 7 so that the air will be evenly distributed and a steady bubble be formed. Thus, as shown in Fig. 8, the incoming air will strike a cylindrical wall and be divided thereby, as indicated by the arrows, and evenly fill the bubble-forming chamber.

I claim:

1. A soap bubble pipe comprising a body having separate bubble-forming means in its bottom and a passage extending outwardly from each means and all the passages terminating in the side of the body, and a stem device extending laterally from the body and through which air can be supplied to any one or more of the passages.

2. A soap bubble pipe comprising a body having separate bubble-forming means, a stem connected with and supplying air to each means, and a mouthpiece having passages into which the stems engage and having a surface against which the lips are adapted to be placed and in which the passages open to permit any one or more of the passages to be covered by the lips while air is blown into any of the other passages.

3. A soap bubble pipe comprising a plurality of bubble forming chambers, a stem leading to each chamber, and a mouth piece having separate openings communicating respectively with the stems.

4. A soap bubble pipe comprising a plurality of bubble forming chambers, and means for supplying air from the mouth to the chamber singly, successively or collectively, said means including a plurality of openings so arranged that one or more can be closed by the lips while air is blown into one or more openings.

5. A soap bubble pipe comprising a plurality of bubble forming chambers, and air conduits leading to the chambers, each conduit including a valve device for controlling the air.

In testimony whereof I have signed my name to this specification in the presence of two subscribing witnesses, this 10th day of April, 1915.

CHATTIN BRADWAY.
